(57) **CLAIM**

The ornamental design for an adapter for mobile grip as shown and described.

DESCRIPTION

FIG. 1 is a top front perspective view of an adapter for mobile grip showing my new design; the top rear perspective view is a mirror image;

FIG. 2 is a top plan view thereof;

FIG. 3 is another top front perspective view thereof;

FIG. 4 is a front elevation view thereof; the rear elevation view is a mirror image;

FIG. 5 is a bottom front perspective view thereof; the bottom rear perspective view is a mirror image;

FIG. 6 is a left side elevation view thereof; the right side elevation view is a mirror image; and,

FIG. 7 is a bottom plan view thereof.
